UNITED STATES PATENT OFFICE.

CONRAD HOFFMAN, OF ELYRIA, OHIO.

TOY.

No. 839,145.

Specification of Letters Patent.

Patented Dec. 25, 1906.

Application filed October 4, 1905. Serial No. 281,227.

To all whom it may concern:

Be it known that I, CONRAD HOFFMAN, residing at Elyria, in the county of Lorain and State of Ohio, have invented a certain 5 new and useful Improvement in Toys, of which the following is a full, clear, and exact description, reference being had to the accompanying drawings.

This invention relates to toys, and has for 10 its object the production of a figure toy in which the toy may be balanced in almost any position, either standing erect on its feet or head or reclining at an angle and supported from some part of the body which rests upon 15 a table or other support. When thus supported, the figure may be swung like a pendulum, the same continuing this motion for a considerable period of time. The device is also adapted for adjustment so as to change 20 the frequency of vibration, or the balancing-lever can be thrown back between the legs of the figure, in which case it will stand erect and appear to be riding a stick.

In the accompanying drawings, forming 25 part of this application, Figure 1 shows a toy consisting of the figure of a man or athlete balanced upon the edge of a table or other support and standing upon its feet, the dotted lines showing the toy in vibrated position. 30 Fig. 2 shows the same toy so adjusted that the figure is resting upon its head. This figure also shows in dotted lines the position the parts assume while swinging. Fig. 3 shows the same toy so adjusted that the 35 figure is resting upon the back of its head and projecting from the edge of the table. Fig. 4 shows the toy standing upon the table with the balancing-lever between its legs, in which position it resembles a boy riding a 40 stick. Fig. 5 is a front view of the device as seen in Fig. 4; and Fig. 6 is a sectional view taken through the ends of the arms of the figure and through the end of the balancing-lever, showing the means for adjusting these 45 parts.

Taking up now a description of the device by reference to the drawings, 1 represents a figure of a man or gymnast reaching forward with his arms 2. Between the outer ends of 50 these arms extends the balancing-lever 3, said lever preferably being considerably longer than the figure and carrying on its lower end a weight 4. This weight may be of any suitable form, but I prefer to construct 55 the same substantially as shown in the drawings, wherein the weight is represented as a

plate of metal with an eye or hole through one end, through which hole the end of the balancing-lever is adapted to extend.

In order to hold the balancing-lever in any 60 desired position relative to the arms of the figure, a bolt or screw 5 is passed through said arms and the lever, said bolt carrying a nut on one end, by means of which the arms and lever may be clamped together, so as to create 65 sufficient friction to hold the arms and lever in any position to which the same may be adjusted. In order to vary the frequency of vibration when the figure is set in motion, the weight 4 may be adjusted up and down 70 on the end of the balancing-lever, said lever being provided with serrations or teeth 6 for this purpose. By simply tilting the weight 4 it will so disengage itself from the lever that it may be moved up and down to any 75 desired point, when it will be held by its engagement with one of the teeth or serrations on the balancing-lever, or it may be removed and turned about one hundred and eighty 80 degrees, so as to throw the center of gravity 85 of the device in a new position, and thus tilt the figure to a new angle. The figure may also be caused to assume a different appearance and different position by removing the weight altogether, as in Figs. 4 and 5, and by 90 turning the balancing-lever backwardly between the legs of the figure, in which case the figure can be poised upon its feet and upon the rear end of the balancing-lever, thereby giving the appearance of a boy riding a stick. 95

By simply turning the balancing-lever at different angles with respect to the arms and by changing the position of the weight the figure can be caused to rest in almost any desired position; but it is believed that a sufficient number of such positions are indicated in the drawings and that it will not be necessary to furnish additional views showing the same.

When the figure is adjusted as shown in 100 Figs. 2 or 3, or in any other position in which the weight is used, the center of gravity of the figure is below the point of support, and when the device is set in vibration it will continue to swing for a considerable period of time, thus affording an instructive and amusing 105 toy.

While I have chosen to show a man as the figure, it will be understood that almost any other form can be substituted therefor.

Having thus described my invention, what 110 I claim as new, and desire to secure by Letters Patent, is—

1. In a device of the character described, a figure, members projecting from said figure, a lever that is adapted to be held between said projecting members, and means for clamping said member and lever together, whereby the latter may be swung to any desired angle with respect to said members and held at such angle.
2. In a device of the character described, a figure adapted to rest upon a support; members projecting from said figure; a balancing-lever carried by said members; means for clamping said members and lever together, whereby the lever may be turned to any desired angle; and a weight carried by said lever below the support for the figure, the said device being adapted to be set in vibration and to rock upon the support.
3. In a device of the character described, a figure adapted to rest upon a support; members projecting from said figure, a balancing-lever carried by said members; a bolt or screw passing through said members and lever whereby the said lever may be clamped at any desired angle with respect to said members; notches or serrations on said lever below the support for the figure; and a weight adjustable upon said lever; said weight being adapted to engage with the serrations thereon.
4. In a device of the character described, a figure adapted to rest upon a support; members projecting from said figure; a balancing-lever carried by said members; means for clamping the members and balancing-lever together so that said lever can be held at any desired angle with respect to the members; notches or serrations on said lever below the support for the figure; a plate having an opening near one of its ends; through which the said lever is adapted to project, said plate forming a weight and being adapted for adjustment on the said lever and for engagement with any of said serrations thereon.
5. In a device of the character described, a figure of a human body having its arms projecting forwardly, a lever projecting between the outer ends of the arms, and means for clamping said lever between the ends of the arms, whereby the said lever is held in any desired position to which it may be turned with respect to said arms.
6. In a device of the character described, a figure of a human body having its arms projecting forwardly, said figure resting upon a support; a balancing-lever held between the outer ends of said arms; a bolt or screw passing through the arms and lever whereby the said arms and lever may be securely clamped together and the lever held at any desired angle with reference to said arms, and a weight carried by said lever below the support for the figure, whereby the figure may be balanced upon the support in different positions, and will vibrate when set in motion.
7. In a device of the character described, a figure of a human body having its arms projecting forwardly, said figure resting upon a support; a balancing-lever carried between the outer ends of said arms; a bolt or screw passing through the arms and lever whereby they may be securely clamped together and the lever held at any desired angle with respect to said arms; notches or serrations on said lever, and a weight adjustable upon said lever; said weight being held in its different positions by engagement with said serrations.
8. In a toy, a figure, arms attached to said figure; a weight-supporting member fast to said arms, and an adjustable balancing-weight on said member.

In testimony whereof I affix my signature in the presence of two witnesses.

CONRAD HOFFMAN.
